UNITED STATES PATENT OFFICE.

JOSEPH A. MARSHALL AND FLAVIUS H. MARSHALL, OF DARLINGTON, IND.

BAND-CUTTER AND FEEDER FOR THRASHING-MACHINES.

SPECIFICATION forming part of Letters Patent No. 309,074, dated December 9, 1884.

Application filed June 18, 1884. (No model.)

To all whom it may concern:

Be it known that we, JOSEPH A. MARSHALL and FLAVIUS H. MARSHALL, citizens of the United States, residing at Darlington, in the 5 county of Montgomery and State of Indiana, have invented certain new and useful Improvements in Band-Cutters and Feeders for Thrashing-Machines; and we do declare the following to be a full, clear, and exact description of the invention, such as will enable others skilled in the art to which it appertains to make and use the same, reference being had to the accompanying drawings, and to letters or figures of reference marked thereon, which form a 15 part of this specification.

Figure 1 of the drawings is a side view of our device. Fig. 2 is a plan view of the same, and Fig. 3 is a detail view.

This invention is an improvement on the 20 patent granted to us on the 29th day of January, 1884, and numbered 292,667; and it relates particularly to an improved form of feeding device in place of that used in the above-mentioned patent.

25 The invention consists, essentially, in constructing the feeding mechanism for the thrasher in the following manner: A proper number of boards having upright serrated edges are attached to a rod by the end that adjoins the 30 carrier in such manner as to have a longitudinal reciprocating movement. The said rod connects two brackets hinged to the carrier, and lies below the level of the carrier-apron. The ends of the boards adjoining the 35 thrasher are reciprocated and vertically vibrated by means of eccentrics fixed on a transverse shaft, which is driven by a pulley on one of its ends and a belt connecting the same with a pulley at any proper point on the thrashing-machine. Each eccentric is set on the 40 shaft in an opposite direction from those adjoining; consequently any two adjacent boards will both vibrate and reciprocate alternately, by the former motion shaking and loosening 45 the cut bundles, and by the latter, in consequence of the serrated edges, carrying the same toward the thrasher.

In the accompanying drawings, A represents the front or receiving end of a thrashing-machine, of which a is the cylinder-shaft, carrying the cylinder a', and having on either end a driving-pulley, a'', the opposite end being

provided with a pulley, a'', to actuate by means of a proper belt the shaft having the eccentrics attached.

55 B is a chute inclined from the carrier to the thrashing-machine, one end of which is pivoted or hinged between the outer ends of the projecting top sills of the thrasher-frame, below the connecting-brackets D D, and the other end loosely attached to the front of the thrashing-machine below, and in proper relation to the cylinder a'. The said chute is provided with upright sides, in which is transversely journaled the eccentric shaft b, provided on one end with the pulley b', and on the other with the pulleys b'' and b''', the former of which is driven by a belt from the pulley a''.

65 b'' b''' are the eccentrics, set at equal distances apart on the shaft b, each being set in an opposite direction to the adjoining ones.

70 C C are the shaking-boards, each provided along its sides with the upright teeth or serrations c c, the vertical edges of which are toward the thrasher and the inclined edges toward the carrier, the said teeth increasing in height as they approach the thrasher. The boards C C have just sufficient space between their edges to move without binding, and each is attached to an eccentric by a band, c', which 75 depends from the lower surface and fits around the eccentric, the latter turning freely in it.

75 If desirable, cranks may be substituted for the eccentric, the cranks turning in proper openings or loops fixed to the lower surfaces of the boards; but the eccentrics are preferable. Each of the boards C has fixed to and depending from the lower surface of its end nearest the carrier a rectangular strap, c'', through which passes a transverse rod, d, that connects 80 the lower ends of the brackets D D. The said strap is just sufficiently wide to admit the rod, but is sufficiently long to allow the board to be reciprocated by the rotation of its attached eccentric.

95 D D are the connecting-brackets, pivoted to and vertically adjustable on the inner ends of the carrier E by means of proper pins or rods, d', and any two opposite holes, e e, the holes being in vertical series one above another and at equal distances apart on each side of the carrier.

100 e' and e'' are the rollers for the carrier-apron, having bearings in the frame of the same, the

former adjacent to the brackets D, and the latter at the opposite end of the frame, and e^3 is the carrier-apron, having below it a proper bearing-board, e^4 , as shown. The journals of 5 the roller e^5 have bearings in a box, e^6 , which slides in ways fixed to the sides of the carrier-frame, and is connected with and controlled by the longitudinal screw e^6 , by means of which the said box may be moved longitudinally and 10 the carrier-apron either tightened or loosened.

e^7 e^8 are legs pivoted on opposite sides of the carrier-frame by their upper ends, their lower ends resting on the ground when the carrier is in working position. The said legs 15 are turned up on the sides of the carrier and the carrier is folded over the top of the thrashing-machine when it is necessary to move the latter.

e^8 is a pulley on the end of the journal of the 20 roller e^5 , outside of the carrier, and situated on the same side of the machine as the pulley b' , being driven by a belt from the same. A cone of pulleys may, if desired, be substituted for the pulley e^8 , so as to give the apron-rollers a 25 greater or less speed, the slack of the apron being taken up, when necessary, by the sliding box e^6 and screw e^6 . The pulleys which drive the carrier-rollers may be arranged in either side of the machine that is desirable.

30 F F are similar vertical brackets, pivoted to the top of each side of the carrier-frame, at opposite points on the same, and having journalled in them the transverse shaft f .

f' is a pulley on the end of said shaft, outside 35 of the carrier, and situated on the same side of the machine as the pulley b' , by which it is driven by means of a cross-belt.

f^3 f^3 are disks provided with continuous

cutting-edges, which disks fit upon the shaft 40 f , and have interposed between them the equal and similar washers, f^4 f^4 . The said washers and disks are secured in place by means of a collar, f^5 , fixed to the shaft on one side of them, and a nut, f^6 , screwing tightly against them on the other side, over a threaded portion of the shaft. The ends of the shaft f are 45 adjustable in the brackets F F by means of the upward-extending arms of said bracket and the horizontal set-screws f^7 f^7 engaging said arms.

50 The operation of the machine is as follows: The bundles are fed to the carrier, which moves them at a greater or less speed (if cone-pulleys are used) toward the cutting-disks. After they are cut by the latter they are 55 thrown into the shaking-boards, which spread them and deliver them upon the chute, whence they fall into the thrashing-machine.

Having thus described our invention, what 60 we claim as new, and desire to secure by Letters Patent, is—

In a feeder for thrashing-machines, the combination of the carrier-frame E, having vertical series of adjustment-holes e , the thrasher-frame brackets D, and pins or rods d' , whereby 65 the said carrier-frame may be vertically adjusted with relation to the thrasher, substantially as specified.

In testimony whereof we affix our signatures in presence of two witnesses.

JOSEPH A. MARSHALL.
FLAVIUS H. MARSHALL.
